UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

HEATING DEVICE

Application filed November 15, 1928. Serial No. 319,583.

My invention relates to improvements in heating devices and more particularly to heating devices comprising radiator units which are provided with cabinet housings or the like.

One of the objects of the invention is to intermittently increase the normal radiating capacity of a heating unit whereby the unit is enabled to meet peak demands above or 10 requirements which exceed the predetermined normal capacity of the unit.

Another object is to diminish the time normally required by a heating unit to heat a room of a given size.

15 Still another object is to provide for discharging vertically moving air currents from a cabinet in a plurality of horizontal directions.

It is frequently desirable to provide a horizontal radiator with a fan, efficient operation of which makes it desirable that the fan be positioned immediately below or above the radiator and that the fan be mounted on a vertical shaft. The combination of such 25 a fan with a horizontal motor rather than a vertical motor is desirable, and a further object of the invention is to provide an improved operative connection between a horizontal motor and a vertical fan.

30 Still another object is to provide improved instrumentalities whereby the deflection, direction and discharge of the heated air arising from the radiator unit can be efficiently controlled in accordance with the requirements of the room and the position of the unit 35 in the room to be heated.

The invention has among its other objects the production of a device of the kind described which is extremely neat in appearance, simple, convenient, compact, durable, reliable, efficient and satisfactory for use 40 wherever found applicable.

Many other objects and advantages of the 45 construction herein shown and described will be obvious to those skilled in the art from the disclosure herein given.

To this end my invention consists in the 50 novel construction, arrangement and combination of parts herein shown and described.

and more particularly pointed out in the claims.

In the drawings, wherein like reference characters indicate like or corresponding parts:

Fig. 1 is a sectional view through a cabinet containing a radiator unit and a motor operated fan;

Fig. 2 is a view along the line 2—2 of Fig. 1; Fig. 3 is a sectional elevational view along 60 the line 3—3 of Fig. 1;

Fig. 4 is a view illustrating an alternative embodiment of my invention which is taken along the line 4—4 of Fig. 5; and

Fig. 5 is a view along the line 5—5 of Fig. 4.

Referring now to the drawings, the numerals 10 and 11 indicate a pair of spaced apart horizontally extending radiator units.

The radiator units 10 and 11 are each supplied with heating fluid which comes through a main feed pipe 12 and branch feed pipes 13. A main vent pipe 15 and a pair of branch vent pipes 14 provide a discharge outlet for the fluid after it passes through the radiator units 10 and 11. Each of the radiator units 10 and 11 comprise a pair of header tanks 16 connected by a plurality of tubes 17. The tubes 17 are positioned in a plurality of transversely extending perforated plates or fins 18 which act as spacers for the tubes.

The radiator units are shown as positioned in a cabinet 23 having two oppositely positioned side walls 24 each provided with an air outlet grille 26. A plurality of outwardly and downwardly extending battens or vanes 27 extend longitudinally of the grilles 26 for a purpose hereinafter more particularly described. The lower portions of the side walls 24 are each equipped with a sieve structure 28. The sieve structures 28 provide entrances for the air and serve to strain and separate the dust particles contained therein before the air passes through the radiator unit.

For the purpose of accelerating the movement of air through the radiator unit, I have provided a fan 30 which is mounted on a vertical shaft 33 and is operated by a horizontal motor 31. I have shown the motor 31 as horizontal rather than vertical, although the in-

vention is equally adapted for use with a vertical motor. The fan 30 and the motor 31 are both supported by a base 32. In Fig. 1, I have shown the fan 30 as mounted above the radiator units 10 and 11. The fan 30 is actuated by the vertical shaft 33 which is positioned between the units 10 and 11. The shaft 33 is held in its vertical position by a brace member 34 which is shown as integral-
 5 ly formed with the support 32. The motor 31 is operatively connected with the fan 30 by a friction wheel 35 which is mounted on the motor shaft and a friction disk 36 which is mounted on the fan shaft 33. It is obvious
 10 that operation of the motor 31 and the fan will accelerate the passage of air through the sieves 28 and upwardly through the radiator units 10 and 11. A rectangular shaped partition or frame 37 having a circular open-
 15 20 ing 38 encloses the radiator units so as to confine the passage of air to the circular area in which the fan 30 rotates.

In order that the heated air coming from the fan 30 may be discharged and generally distributed throughout the room, I have provided in the upper portion of the cabinet 23 an instrumentality 40 which is made up of a pair of arcuate shaped plates 41. The plates 41 are oppositely curved upwardly and outwardly, having their inner edges vertical and connected at the middle of the cabinet 23. The outer edges of the plates terminating in the side walls 24 of the cabinet immediately above the grille openings 26. The plates 41 take a general horizontal direction at their intersection with the side walls 24. The fan 30 drives the air currents with a considerable velocity against the arcuate plates 41 with the result that the column of air is directed horizontally through the grilles 26 and leaves the cabinet in a generally horizontal direction with a considerable velocity.

Figs. 4 and 5 illustrate an alternative embodiment of the invention in which the upper portion of the cabinet 23 differs from the embodiment shown in Figs. 1 and 3, in that it has grilles 26 in all four of its side walls 24. Each of the four grilles 26 is equipped with vanes 27. An instrumentality 42 is positioned to deflect the rising air currents outwardly through the grilles 26. The instrumentality 42 is constructed of four arcuate shaped plates 43 which curve upwardly and outwardly to form an inverted pyramid having curved side walls. The plates 43 are of generally triangular shape meeting at the center of the cabinet 26, and have their opposite base edges terminating in the side walls 24 of the cabinet at the top of the grilles 26. The plates 43 each take a generally horizontal direction at their intersection with the side walls 24, so that the air is driven against the vanes 27 in a generally horizontal direction.

65 In practice I find that devices of this kind

which are of sufficient size to heat lofts and factory units are necessarily of considerable height. In such cases the heated air may be discharged from the cabinet at a point some seven or eight feet above the floor, and in order that the lower spaces of the room may be properly heated I have provided the vanes or batten plates 27 which tend to direct the air downwardly and outwardly as it leaves the grilles 26.

70 Thus it will be seen that I have provided a heating apparatus which is adapted to heat rooms of all sizes and especially to heat large rooms such as lofts, and factories or the like, and in which the air is strained before heating and is directed outwardly and downwardly from the cabinet and over the room in such a way as to tend to uniformly heat the room.

Having thus described my invention, it is 85 obvious that various immaterial modifications may be made in the same without departing from the spirit of my invention; hence I do not wish to be understood as limiting myself to the exact form, construction, 90 arrangement and combination of parts herein shown and described or uses mentioned.

What I claim as new and desire to secure by Letters Patent is:

1. A heating device comprising an open ended cabinet containing a radiator unit supported by said cabinet, a fan positioned adjacent the radiator unit, providing means to accelerate vertical movement of air through the unit, an annulus extending from the radiator unit and surrounding the fan, said cabinet having a plurality of outlet openings for the heated air, and an instrumentality adapted to deflect and to discharge the air through said openings in a generally horizontal direction.

2. A heating device comprising a cabinet containing a radiator unit, a fan providing means for causing movement of air vertically through said unit, a member cooperating with the fan and radiator unit providing means facilitating said movement, a plurality of openings forming an outlet for the heated air, said openings forming a substantially continuous grille in the perimeter of the cabinet above said member, and an instrumentality adapted to discharge the air horizontally through said openings.

In testimony whereof, I have hereunto signed my name.

120 ARTHUR B. MODINE.
